UNITED STATES PATENT OFFICE.

CHARLES H. O'BRIEN, OF AUGUSTA, MAINE.

ELECTRICAL APPARATUS FOR PRODUCING SOUND-SIGNALS.

No. 926,284.

Specification of Letters Patent.

Patented June 29, 1909.

Application filed December 11, 1905. Serial No. 291,233.

To all whom it may concern:

Be it known that I, CHARLES H. O'BRIEN, citizen of the United States, residing at Augusta, in the county of Kennebec and 5 State of Maine, have invented certain new and useful Improvements in Electrical Apparatus for Producing Sound-Signals, of which the following is a specification, reference being had therein to the accompanying 10 drawing.

My present invention relates to improvements in electrical apparatus for producing sound signals, the main object being the production of sound signals for automobiles, 15 launches and the like where a greater sound is desired than with the apparatus as set forth in my Patent #974,245, patented July 11, 1905.

The sound produced by the apparatus as 20 set forth in the above named patent is round and clear, but with the construction as set forth in this application of electrodes in loose contact on armature which is centrally attached to diaphragm, I secure greater latitude of vibration consequently more intense 25 sound and is more especially desirable in autos, launches and electric cars. This apparatus consists primarily of an amplifier carrying a diaphragm, an electro-magnet, 30 adapted to operate an armature, which carries a circuit interrupter; the armature and the diaphragm being connected together so that vibrations of the armature are mechanically transmitted to the diaphragm. For 35 this purpose I also intend to dispense with the use of the button as set forth in the above mentioned patent, preferring to shake the electrodes in loose contact to act in combination with the prong of the armature.

40 In the accompanying drawings:—Figure 1 is a sectional view of a sound producing body, the resonator showing one form of arranging the apparatus, the electrical circuit being in diagram. Fig. 2 is a similar view of a modified form.

45 Referring to the drawings,—the numeral 1 designates the amplifier which is connected to a casing 2 provided with a removable cap 3. Formed within the casing is an inwardly 50 projecting annular rim 4 to which is connected the diaphragm 5 preferably made of brass. Connected centrally of the diaphragm and projecting from the opposite side from the amplifier is a prong or pin 6 which is connected to the outer end of the pivotally 55 mounted armature 6^a whose other end is piv-

otally connected to the plate 7 carried by the bracket 8, the said bracket being provided with a long arm 9 for supporting the electro-magnet 10 and with a short arm 11 to which is connected a contact arm 12 whose upper end is adapted to contact the point 13 carried by the armature and opposed to one pole of the electro-magnet. As shown a button 14 is secured to the wall of the casing and contains particles of carbon as in my former patent No. 794,295 and is used in the same manner as a variable resistance, wire 15 connecting the contact arm and said button while the wires 16 and 17 are connected to the posts 18 and 19 to the batteries 20 and push button 21. By this construction it will be seen that upon establishing a circuit by means of the push button, the electro-magnet operates or vibrates the armature, which in turn through the medium of the prong vibrates the diaphragm and the circuit interrupter so as to produce a sustained or intense sound.

In Fig. 2, the electro-magnets 26^a, are carried by the arm 27, which has a tension upwardly, and by means of the screws 28, the electro-magnets are moved to or from the armature 28^a.

From the foregoing description taken in connection with the drawings, it is evident that I provide a new and improved construction of an apparatus of this character in which a brass diaphragm is used in combination with a pivoted armature which is provided with a prong connected centrally of the diaphragm and to the armature so that all of the pull and the vibration is centered into the center of the resonator and therefore free for action.

95 What I claim as new and desire to secure by Letters Patent is:

1. In an apparatus of this character, the combination of a sound producing body, a diaphragm, a vibrating armature connected centrally of the diaphragm, said armature being provided with contacts, an electro-magnet for vibrating the armature, an electrical source of energy, and means for adjusting the electro-magnet with relation to the 100 armature.

2. In an apparatus of this character, the combination of an electro-magnet, a sound producing vibrating body capable of being vibrated, an armature actuated by the 110 electro-magnet and connected to the diaphragm, a source of electrical energy, means

for causing electricity to flow from the source, and means for adjusting the electro-magnet with relation to the armature.

3. In an apparatus of this character, the combination of an electro-magnet, a sound producing vibrating body capable of being vibrated directly by said electro-magnet, an armature capable of being vibrated by said electro-magnet connected centrally to the sound producing body, a source of electrical energy, means for causing the electro-magnet to be energized, and means for adjusting the electro-magnet with relation to the armature.
- 10 4. In an apparatus of this character, the combination of an electro-magnet, a sound producing vibrating body capable of being vibrated, an armature adapted to be vibrated by the electro-magnet having one end connected 20 to the center of the sound producing body, contacts carried by the armature, a source of electrical energy, means for causing electricity to flow from the source through the electro-magnets and contacts, and means 25 for adjusting the electro-magnet with relation to the armature.
5. In an apparatus of this character, a casing, an amplifier carried thereby, a diaphragm mounted within the casing, an electro-

magnet mounted within the casing, an armature pivotally mounted to be operated upon by the electro-magnet having one end connected to the diaphragm, a source of electrical energy, means for causing the electricity to vibrate the armature, and a cap carried by the casing, and means for adjusting the electro-magnet with relation to the armature.

6. In an apparatus of this character, the combination of a casing, an amplifier carried thereby, a diaphragm mounted within the casing, an electro-magnet mounted within the casing, an armature pivotally mounted to be operated upon by the electro-magnet and having one end connected to the diaphragm, contacts adapted to contact the armature as the same is being vibrated, a source of electrical energy, means for causing electricity to vibrate the armature, a cap carried by the casing, and means for adjusting the electro-magnet with relation to the armature.

In testimony whereof I affix my signature in presence of two witnesses.

CHARLES H. O'BRIEN.
